UNITED STATES PATENT OFFICE.

JAMES H. KEIDERLING, OF BOUND BROOK, NEW JERSEY.

BOGIE-TRUCK.

No. 890,064.

Specification of Letters Patent.

Patented June 9, 1908.

Application filed February 28, 1906. Serial No. 303,355.

To all whom it may concern:

Be it known that I, JAMES H. KEIDERLING, a citizen of the United States, residing at Boundbrook, in the county of Somerset and State of New Jersey, have invented an Improvement in Bogie-Trucks, of which the following is a specification.

This invention relates to bogie trucks designed especially for use in machine shops, 10 railway rail shops and like places for moving heavy bodies to points in the shops which the traveling cranes cannot reach, and has for its objects to produce a comparatively simple, inexpensive device of this character which 15 will possess the requisite strength and durability, one wherein the truck may be readily manipulated for depositing the load carried thereby into a certain predetermined position, and one in which the upper frame or 20 turn table will be susceptible of free movement.

With these and other objects in view, the invention comprises the novel features of construction and combination of parts more 25 fully hereinafter described.

Figure 1 is a reverse plan view of a truck embodying the invention, parts of the truck being shown in dotted lines. Fig. 2 is a side elevation of the device. Fig. 3 is a sectional view taken centrally and longitudinally through the truck on the line 3—3, Fig. 1. Fig. 4 is a side elevation of one of the side rails of the frame. Fig. 5 is a similar view of one of the end bars of the frame. Fig. 6 is a 35 view in elevation of the swivel plate lock pin. Fig. 7 is a side elevation of one of the roller shafts.

Referring to the drawings, it will be seen that the device embodies a lower frame comprising side rails 1 and end bars or members 2 having terminal tenons 3 adapted to fit in suitable mortises or perforations 4 formed in the rails 1 at points near their ends, there being attached to the lower faces of the rails 1 bearing members or journals 5 provided with suitable bearing openings to receive the circular portions or spindles 6 formed on the ends of squared shafts or axles 7 extended centrally and longitudinally through the 50 rollers 8 on which the truck is mounted for travel.

Attached to the upper face of the lower frame is a circular swivel plate 9 provided with a central opening 10 and with an annular raceway 11 formed to receive anti-friction members or balls 12 disposed between said

plate and an upper swivel plate 13 corresponding to the plate 9 and having a central opening 14 and on its lower face an annular raceway 15 which conjointly with the raceway 11 accommodates the anti-friction balls. 60

Fixed upon the upper face of the upper swivel plate 13 is an upper supporting frame similar in form to the lower frame and comprising side rails 16 and end bar 17 provided with terminal tenons 18 formed to fit transverse openings or sockets 19 provided in the rail 16, the bars 2 and 17 being fixedly attached to their respective side rails by means of vertical coupling pins 20 entered through alined openings formed in the rails and in the tenons formed on the ends of the bars. 70

The plates 9 and 13 which constitute a turn table are pivotally connected for rotation one upon the other by means of a vertical pintle or bolt 21 entered through the openings 10 and 14 which are arranged in alinement, the plates being attached to their respective frames by means of bolts 22. 75

In practice, the load to be transported by 80 the truck is arranged upon the upper frame and the truck moved from place to place during which operation it travels upon the rollers 8 as will be readily understood. After reaching the point of destination the load 85 carried upon the truck is deposited in a manner which will be apparent, it being understood, however, that the upper frame may, owing to the interposed turn table, be readily shifted upon the lower frame in order that 90 the articles on the truck may be arranged in a certain predetermined position; for example, if the truck be used for transporting railway rails the upper frame may be shifted to the requisite position in order that the 95 rails may be properly piled in alinement. During the movements of the upper frame the anti-friction balls 12 permit of the upper plate 13 turning freely upon the lower plate 9.

It is to be noted that the device herein described while of simple construction will be exceedingly strong and durable, thereby rendering it effective in the handling of very heavy loads, such as will be met with in locomotive factories, railway rail shops, and machine shops, and furthermore, that parts of the device which may become defective through wear or other causes may be conveniently renewed as circumstances require. 100 105

What I claim is:

1. A truck of the type described comprising a lower frame, a swivel plate attached 110

thereto and provided with an annular raceway, an upper frame having a swivel plate attached therebeneath and provided with an annular raceway opposed to the first-
5 named raceway, anti-friction balls arranged between said plates within the raceways, bearings attached beneath the lower frame, rollers on which the truck is arranged for travel, and axles extended longitudinally
10 through said rollers and having terminal journals disposed for rotation in said bearings.

2. A truck of the type described comprising an upper and a lower frame, each consisting of side bars provided with sockets, and end bars having tenons fitted in said
15 sockets, coupling pins extended through the

side bars and tenons, a turn table interposed between the frames and comprising a pair of swivel plates provided with central bearing openings and with opposed raceways, a pin-
20 tle connecting said plates, anti-friction devices disposed in the raceways between the plates, and rotary transporting members arranged beneath the lower frame and on which the truck travels.

25

Signed by me this 23d day of February
1906.

JAMES H. KEIDERLING.
